UNITED STATES PATENT OFFICE

149,046

DESIGN FOR A HOSTESS TRAY

David Blumenthal and Herman L. Seiden, Chicago, Ill., assignors to Phil-Mar Mfg. Corp., Chicago, Ill., a corporation of Illinois

Application June 22, 1946, Serial No. 130,934

Term of patent 14 years

(Cl. D44—10)

To all whom it may concern:

Be it known that we, David Blumenthal and Herman L. Seiden, citizens of the United States of America, both residing at Chicago, in the county of Cook and State of Illinois, have invented a new, original, and ornamental Design for Hostess Tray, of which the following is a specification, reference being had to the accompanying drawing, forming part thereof.

Fig. 2 is a side view thereof.

Fig. 3 is a plan view, partly in section, taken on the line 3—3 of Fig. 2.

We claim:

The ornamental design for a hostess tray, as shown.

DAVID BLUMENTHAL.
HERMAN L. SEIDEN.
